UNITED STATES PATENT OFFICE.

BENJAMIN T. BROOKS AND IRWIN HUMPHREY, OF PITTSBURGH, PENNSYLVANIA,
ASSIGNORS TO GULF REFINING COMPANY, OF PITTSBURGH, PENNSYLVANIA, A
CORPORATION OF TEXAS.

MANUFACTURE OF GLYCOLS.

1,215,903.

Specification of Letters Patent. Patented Feb. 13, 1917.

No Drawing.

Application filed March 23, 1916. Serial No. 86,063.

To all whom it may concern:

Be it known that we BENJAMIN T. BROOKS and IRWIN HUMPHREY, both citizens of the United States, residing in Pittsburgh, Allegheny county, State of Pennsylvania, have invented certain new and useful Improvements in the Manufacture of Glycols; and we do hereby declare the following to be a full, clear, and exact description of the invention, such as will enable others skilled in the art to which it appertains to make and use the same.

This invention relates to the production of glycols or mixtures of glycols from dichlorinated hydrocarbons of the ethylene series or mixtures thereof.

The dichlorinated hydrocarbons which are used for the production of the glycols, according to the present invention, may be the individual dichlorinated hydrocarbons such as ethylene dichlorid or Dutch liquor, or similar chlorids. The mixture of dichlorids which is produced from the unsaturated hydrocarbons of oil gas is of particular value in this process for the reason that it can be readily prepared from the oil gas by inexpensive methods and for the further reason that it permits the production therefrom by a single process of a mixture of glycols adapted for use to advantage directly as a mixture or for the production therefrom of the individual glycols.

Oil gas, when suitably produced, is rich in olefins, and particularly in olefins of the ethylene series. The average oil gas may thus have from 33 to 43% of olefins, the remainder of the gas being of hydrogen and saturated hydrocarbons in varying proportions. The olefins or unsaturated hydrocarbons of the oil gas consist principally of ethylene and propylene, but small amounts of other hydrocarbons such as butylene, amylene, benzol, etc., may also be present. The relative proportions of ethylene and propylene will also vary with different oil gases depending upon the method of production of the gas, the material from which produced, etc. The relative amounts of ethylene and propylene can also be varied and to a certain extent regulated by the method

of producing the oil gas, and, accordingly, the product obtained from the oil gas can be correspondingly regulated. Thus, in utilizing oil gas for producing glycols, the relative proportions of ethylene and propylene 55 glycols can be somewhat regulated by regulating the proportions of the hydrocarbons in the oil gas from which the dichlorids are produced.

When oil gas is used as the source of the 60 unsaturated hydrocarbons from which the dichlorids are produced, the production of the oil gas and of the dichlorids therefrom can be effected in any suitable manner. It will be understood by those skilled in the 65 art that various methods of producing the oil gas and of chlorinating the gas to produce the dichlorids are available for these purposes.

According to the present invention, the 70 dichlorinated hydrocarbons of the ethylene series, separately or in admixture with each other, are caused to react with an alkali formate in the presence of an organic solvent such as methyl alcohol. The reaction of the 75 dichlorinated hydrocarbon and the alkali formate results in the production of the formyl derivative or formate of the corresponding hydrocarbon or hydrocarbons, alkali chlorid being at the same time set free. 80 The formates thus formed are acted upon by the methyl alcohol to give the corresponding glycol or glycols and methyl formate.

It has been heretofore proposed to produce 85 glycols by conversion of the chlorids into acetates and recovery of the glycols from the diacetates. This process, however, requires expensive apparatus, a silver lining being commonly used to resist the glacial 90 acetic acid utilized. The acetate method is, moreover, one in which small yields of the glycol are obtained, for example, yields of about 35% of the theoretical.

The novel method of the present invention 95 can be practised in simple and inexpensive apparatus and with yields as high as 80% or higher. Such yields are much higher than could *a priori* be expected, from analogous processes of the prior art.

The following more detailed description will illustrate what we now believe to be the condition for securing the optimum results in the practice of the invention.

5 A mixture of the dichlorids such as is obtained from oil gas is heated with a slight excess (say 1½ to 2 times the theoretical) of the alkali formate. We consider sodium formate better than the potassium formate 10 for the reason that it is not hygroscopic and is cheaper and more easily obtained. An excess of say three to five volumes of methyl alcohol is also added, and the resulting mixture is heated in an autoclave to a temperature 15 of about 180° C. and under a maximum pressure of about 260 lbs. for about five or six hours. The pressure may be generated within the autoclave by heating to the temperature indicated. If thus the autoclave is 20 two-thirds full, the pressure will attain a value of, for example, 200 to 260 lbs. The temperature of the heating may be varied somewhat, for example, between 140° C. to 200° C.; and the pressure can also be varied, 25 for example, between 100 lbs. and 260 lbs.

The reaction is promoted by stirring or agitating the contents of the autoclave, and this agitation can, in practice, be obtained, for example, by rotating the autoclave.

30 It will be noted that the process is easily carried out in simple apparatus and with methyl alcohol as the solvent and as one of the reagents taking part in the operation. The process is thus much more advantageous 35 than the acetate method, both in its method of procedure and in the increased results obtained.

After the operation is completed, the liquid contents are separated from any salt 40 formed, by filtration, or in any other suitable manner, and the liquid mixture is then subjected to fractional distillation to recover therefrom the different constituents. The excess of methyl alcohol and the methyl 45 formate are first removed and can be recovered for re-use or for further treatment. The glycals, having higher boiling points, are preferably distilled *in vacuo* in order to avoid decomposition. Higher temperatures, such 50 as would cause decomposition, are similarly avoided during the main reaction, for the same reason.

Where a mixture of glycals is obtained, as 55 is the case where a mixture of dichlorinated hydrocarbons such as are obtained from oil gas is used as the starting material, this mixture can be directly used or it can be further fractionated and the separate glycals (ethylene glycol, propylene glycol, etc.,) re- 60 covered therefrom.

The methyl formate resulting from the process can be subjected to a suitable saponification with caustic alkali and the alkali

formate thereby regenerated for further use. It will thus be seen that the process is one of 65 notable economy in that expensive reagents are not required and in that the alkali formate and the methyl alcohol are to a greater or less extent recovered in a form suitable for re-use.

As above pointed out, the mixture of dichlorinated hydrocarbons obtained from oil gas is of particular value in the practice of the invention for the reason, among others, that the resulting mixture of glycals is produced directly and is available for use as such or as a source of the individual glycals. When a mixture of the dichlorinated hydrocarbons is thus used, the formation of the different glycals proceeds smoothly and simultaneously with the resulting production of the glycol mixture.

What we claim is:

1. The method of producing glycals from dichlorinated ethylene hydrocarbons, which 85 comprises subjecting such hydrocarbons to reaction with an alkali formate in the presence of an alcohol; substantially as described.

2. The method of producing glycals from dichlorinated ethylene hydrocarbons, which 90 comprises heating the same under pressure with an alkali formate and an alcohol; substantially as described.

3. The method of producing glycals from dichlorinated ethylene hydrocarbons, which 95 comprises heating the same to a temperature of about 140 to 200° C. and a pressure of 100 to 260 lbs. together with an alkali formate and an alcohol; substantially as described.

4. The method of producing glycals from dichlorinated ethylene hydrocarbons, which comprises subjecting the same to the action of sodium formate and methyl alcohol; substantially as described.

5. The method of producing glycals from dichlorinated ethylene hydrocarbons, which comprises heating the same to a high temperature and pressure in the presence of sodium formate and methyl alcohol; substantially as described.

6. The method of producing a mixture of glycals from a mixture of dichlorinated ethylene hydrocarbons, which comprises subjecting the mixture of dichlorinated hydrocarbons to reaction with an alkali formate and an alcohol; substantially as described.

7. The method of converting dichlorinated hydrocarbons into diformates, which comprises heating the same with alkali formates in the presence of an organic solvent; substantially as described.

8. The method of converting diformyl derivatives of hydrocarbons into glycals, which comprises heating the same with an 125 alcohol; substantially as described.

9. The method of producing glycols from dichlorinated hydrocarbons, which comprises subjecting the dichlorinated hydrocarbons to reaction with an alkali formate and an alcohol and thereby producing the glycols and the formate of the alcohol, and saponifying the formate and thereby recov-

ering the alkali formate for further use; substantially as described.

In testimony whereof we affix our signatures.

BENJAMIN T. BROOKS.
IRWIN HUMPHREY.
